GEORGE HOWLETT DAVIS, OF WEST ORANGE, NEW JERSEY.

RESPOOLING DEVICE FOR MUSIC-ROLLS.

968,136.

Specification of Letters Patent. Patented Aug. 23, 1910.

Application filed December 18, 1907. Serial No. 407,025.

To all whom it may concern:

Be it known that I, GEORGE HOWLETT DAVIS, a citizen of the United States, residing in the town of West Orange, county of 5 Essex, and State of New Jersey, have invented certain new and useful Improvements in Respooling Devices for Music-Rolls; and I do declare the following to be a full, clear, and exact description of the 10 same, such as will enable those skilled in the art to which it pertains to make, construct, and use the same.

My invention relates to devices for respooling perforated music rolls of the character and kind used upon so-called automatic or player pianos. In the manufacture of music rolls of this character the rolls of paper to be perforated are fed into the perforators in layers frequently as many as 20 sixteen-ply, that is to say, sixteen rolls of paper have their ends inserted into the perforating machine, and the sixteen rolls are operated upon simultaneously. If the sixteen-ply were immediately wound up in a 25 single sixteen-ply roll, the paper would become so distorted and buckled as to render the individual rolls useless. It is necessary, therefore, that the complete gang of sixteen rolls shall be re-spooled or re-wound into 30 individual rolls.

I will now proceed to describe this specific mechanism forming my invention.

Figure 1 is a side elevation of the complete structure. Fig. 2 is a plain view 35 partly in section. Fig. 3 is a detached view of the feed roller locked.

The structure is composed of the supporting frame 1, upon the upper side of which and near one of its longitudinal edges are 40 mounted the two semicircular spindle supports 2 and 3, secured to the corners of the frame in any convenient or desired manner.

Pivotedly carried between spindle supports 2 and 3 are the several spindles 4, 45 there being in the example illustrated sixteen of such spindles, which project forwardly or toward the front side of the machine and over-hang the main portion thereof, as illustrated in Fig. 2.

50 Between the semicircular supports 2 and 3 and secured to each individual spindle is a pulley 5, so arranged that all of the pulleys lie in the same vertical plane. Mounted upon the top of the frame 1, near one end thereof is the shaft 6, such shaft carrying upon its outer end a fly-wheel or pulley 7,

and near its inner end the pulley 8, which is in vertical alinement with the series of pulleys 5, so that a single belt 9 passing over the drive pulley 8 and the series of pulleys 5 will simultaneously drive all of the pulleys 5 and with them the over-hanging spindles.

If desired the shaft 6 may be provided with a drive pulley so as to be driven by means of belt power. Located substantially 65 in the center of the circle formed by the two spindle supports 2 and 3 are the two tension pulleys 10 and 11, the pulley 10 being mounted in fixed bearings 12 upon the upper side of the frame, while the pulley 11 is 70 mounted upon a pair of swinging arms 13, located on the inner face of the upper members of the frame 1. These arms are held under spring tension by means of the spring 14 one end of which is secured to the outer 75 end of the arm 13, while the other end is secured to the frame member 1.

In order to hold the pulleys 10 and 11 separate during the process of threading up the machine, I provide the pawl 15 upon the 80 inside of the frame, said pawl having a pair of notches to engage the shaft of the pulley 11, as clearly indicated in Fig. 3. Upon the right-hand side of the frame as indicated in Fig. 1, I mount a table 16, extending from 85 the edge of the frame beneath the tension roller 10, and provided with the adjustable guides 17 at its edges.

At the outer end of the table and secured to the edge of the frame, as indicated in 90 Fig. 1, I secure the roller racks, such racks comprising the two arms 18, having a plurality of spindles or rollers 19 mounted therein. At the opposite side of the frame 1, I mount another inclined table 20, such table 95 being so located as to cover the shaft 6, and thus protect the same from contact with the music rolls.

If desired, a belt tightening device, such as illustrated in Fig. 1, at 21, may be provided to take up the slack in the belt 9 heretofore referred to.

In the use of my improved re-spooling machine, the perforated music rolls in the form in which they come from the perforating machines are in racks or trays, such as that illustrated at 22, the combined series of rolls being held together by means of the ordinary paper clips and lying loosely folded in such racks 22. When ready for spooling 105 the upper or outside end of the bunch of perforated paper 23 is carried up and 110

threaded over and under the several spindles 19, whence it is carried across the table 16 between the adjustable guides 17 and beneath the roll 10, it being understood that 5 the ends are carried between the rolls 10 and 11 while the roll 11 is held away from the roller 10 through the pawl 15. The combined ends of the rolls are then carried forward and laid upon the table 20 when each 10 one is taken up separately and carried over to the right, as shown in Fig. 1, and given a turn or two around the first spindle at the right. The second layer is then taken and given a turn or two upon the second spindle 15 and the third to the third spindle and so on until the entire number of layers of paper 20 are started upon the spools. When so started the completion of the spooling is effected by the rotation of the shaft 6 by the crank upon the end thereof.

In the spooling of perforated rolls of this character I have found that it frequently happens, from one cause or another, that one 25 of the layers of paper will begin to wind a little more rapidly than the others. If some means were not provided for maintaining a uniform tension in that portion of the several layers of paper 23 lying between the spindle and the tension rollers 10 and 11 30 there would result a buckled and crinkled effect in those particular layers of paper having the least tension. I have found, however, that in arranging the individual spindles horizontally, and collectively, in a semi- 35 circle with the belt 9 lightly contacting the peripheries of the several pulleys 5, should undue tension exist in any one or more of the layers, then the belt would slip over the corresponding pulley until the tension would 40 be equalized in all of the several layers during the said winding process. It is this slip of the belt resulting in the proper regulation of the tension that constitutes the successful operation of the machine.

45 When the bunch of paper is completely wound, the rolls are taken off from the several spindles, when they are ready for the next step in their process of completion and a new tray full of unwound rolls is prepared 50 for re-spooling in the manner hereinbefore set forth.

In order to facilitate the starting of a 55 layer of paper upon the spindle, I provide each of the spindles with diametrical notches 24 to receive corresponding pins upon a crank 25, such crank being detachable from each of the spindles and successively applied thereto for the purpose of starting the end of a layer upon the corresponding spindle.

60 In order that the belt may have a uniform bearing upon the active spindles 5 at the ends of the supporting frames 2 and 3, I prefer to insert two terminal pulleys 26, so that the belt or band 9 will have no greater 65 area of contact upon the terminal pulleys 5

than upon the intermediate pulleys. It will be readily seen that if the belt or band 9 passed directly from the drive pulley 8 to the terminal spindle pulleys, there would be a greater area of contact between such band 70 and said pulleys resulting in a reduced tendency to slip under tension of the terminal rolls.

I believe that I am the first to produce a re-spooling device for music rolls or other 75 multiple layers of paper of the character heretofore described, wherein provision is made for uniform tension in the several layers by means of a slip belt, and I, therefore, desire to claim such a device broadly. 80

I claim—

1. In a re-spooling machine, the combination of a supporting frame, a plurality of parallel spindles, mounted upon said frame, means for simultaneously rotating said spindles and means for maintaining a uniform tension in the materials to be wound upon said spindles. 85

2. In a re-spooling machine, the combination of a semicircular supporting frame, a plurality of parallel spindles mounted in said frame means for simultaneously rotating said spindles, and means for maintaining a uniform tension in the materials to be wound upon said spindles during their ro- 95

90 3. In a re-spooling machine, the combination of a vertically arranged semicircular spindle frame, a plurality of parallel horizontal spindles mounted in said frame, means for simultaneously rotating said spindles, 100 means for maintaining a uniform tension in the materials to be wound upon said spindles during their rotation.

4. In a re-spooling machine the combination of a vertically arranged semicircular spindle frame, a plurality of parallel spindles mounted in said frame, each of said spindles being provided with a driving pulley, an endless belt passing over all of said 105 pulleys and having slipping contact therewith, a pair of tension rolls, centrally located with respect to said spindles, for producing a uniform tension in the several layers of material passing therebetween to be 110 wound upon said spindles. 115

5. In a re-spooling machine, the combination of a spindle frame, a plurality of parallel spindles arranged in the arc of a circle 120 upon said frame, a pulley secured to each spindle, a driving belt or band upon said pulleys, means for driving said belt or band to simultaneously rotate all of said spindles, a pair of tension rollers centrally located with respect to said spindles, and guiding 125 devices for guiding materials to be wound upon said spindles to said tension rolls.

6. In a re-spooling machine, the combination of a plurality of parallel spindles arranged in the arc of a circle, a pair of ten- 130

sion rolls located at the center of said circle, means for guiding multi-ply materials to and between said rolls and to said spindles to be wound thereon, and means for simultaneously rotating said spindles.

7. In a re-spooling machine the combination of a plurality of parallel spindles arranged in the arc of a circle, pulleys secured to said spindles, an endless belt or band 10 passing over said pulleys and having slip-

ping contact therewith, means for driving said belt or band to simultaneously rotate said spindles.

This specification signed and witnessed this 10th day of December 1907.

GEORGE HOWLETT DAVIS.
